AUTOMATIC INFEED MECHANISM

William Mignona, Pottstown, Pa.

Application November 27, 1946, Serial No. 712,489

5 Claims. (Cl. 51-2)

1

This invention relates to grinding machines and is particularly directed to an automatic in-feed attachment for such machines.

An object of the invention is to provide automatic means to actuate the hand feed lever of a grinding machine in such a manner that uniform stock removal from the piece being ground is insured.

Another object of the invention is to provide an automatic in-feed attachment for machines of this type which can be easily installed without altering the basic structure of the machine.

A further object of the invention resides in the provision of an hydraulic feed attachment, rendered effective upon partial movement of the hand feed lever, to move the feed lever through its feed range to stop position.

Further objects and advantages will become apparent from a study of the following description when taken in connection with the accompanying drawing in which:

Figure 1 is a front elevation of a grinding machine incorporating the invention;

Figure 2 is a fragmentary end view of the machine shown in Figure 1;

Figure 3 is an enlarged sectional detail of the catchblock;

Figure 4 is an enlarged sectional detail of the valve structure of the mechanism;

Figure 5 is a side elevation of the cylinder with parts broken away and others shown in detail; and

Figure 6 is an enlarged view of a modified form of cam.

Referring to the drawing, the numeral 10 indicates a centerless grinding machine which incorporates the present invention. The machine 10 is provided with a hand in-feed lever 12 capable of causing relative movement between a pair of grinding wheels 14 and 15, between which the piece being ground is positioned and rotated during the grinding operation. When the hand lever is manually operated throughout its entire feed range, the operator is obliged to use extreme caution to prevent erratic movement which causes an uneven rate of stock removal resulting in certain heat-tempering of the hardened work surfaces resulting in loss of metallurgical quality.

To overcome the undesirable features of manual operation, the machine 10 has been provided with automatic means to operate the lever 12 during its feed movement. The automatic means, preferably in the form of an attachment readily applied to grinding machines of the type illustrated, comprises a cylinder 18 conveniently at-

2

tached to the machine by means such as the bracket 20. The cylinder 18 contains a piston 19 of suitable form having a piston rod 22 extending from the cylinder into the path of movement of the lever 12, the bracket 20 being affixed to the machine to so locate the cylinder and piston rod. The outer end of piston rod 22 is provided with a catch-block 24, shown in detail in Figure 3. Catch-block 24 is provided with a notch 25 for receiving a slide bracket 27 mounted on the lever 12, means in the form of oppositely disposed spring pressed poppets 29 projecting into notch 25 serving to latch the bracket 27 and block 24 together when the lever is moved into position to permit such engagement.

Connected to the top and bottom of cylinder 18 are fluid supply pipes 31 and 32 respectively, leading from a two-way control valve 35 of a well known type, which is in turn connected to a source of hydraulic fluid under pressure. The source of hydraulic pressure may be provided by the grinding machine itself and is sufficient to actuate the feed mechanism. As illustrated in Figure 4, the valve 35 contains a spring pressed piston or plunger 37 which permits fluid flow to one cylinder port while exhausting the other port. The plunger is actuated by means of a cam 40 mounted on the base of the hand feed lever 12, the cam being located so as to engage the plunger 37 simultaneously with the engagement of slide bracket 27 and block 24. Thus, the valve 35 is actuated to supply fluid to the top of cylinder 18 upon interlocking of the lever 12 with the piston rod 22 to move the lever 12 through its feed range. The use of hydraulic fluid for this purpose insures smooth constant feed and avoids the undesirable features of the manual feed.

In order to unlatch the slide bracket 27 from the catch block 24, the stroke of the piston 19 is such that lever 12 engages and is stopped by bracket 20 prior to completion of the downward movement of the piston 19. At this limit of the feed movement, the operator can raise the lever 12, to return the lever to starting position which movement also disengages the cam 40 from the valve plunger 37. Plunger 37 returns to the position shown in Figure 4 to exhaust fluid from the top of cylinder 18 and supply fluid to the bottom of the cylinder which action moves the piston rod 22 to its starting position, again putting the catch-block 24 into feed position.

The contour of cam 40 is such that the stock removal from the piece being ground is continuous and at a predetermined rate. In order to vary the feed in instances where a continuous, unin-

terrupted grinding operation would produce undesirable heat tempering of the hardened surfaces, the cam may be modified as shown in Figure 6. Cam 40' is illustrative of an arrangement for interrupting the grinding action at predetermined intervals to permit periodic cooling of the piece. Thus, it will be understood that by forming the cam of pre-calculated contour, any practical rate and degree of stock removal may be obtained.

What I claim is:

1. The combination with a grinding machine having a hand feed lever, of a cylinder, a fluid actuated piston in said cylinder having a piston rod projecting from said cylinder into the path of said hand feed lever, interlocking elements associated respectively with said piston rod and hand feed lever engageable upon movement of said hand feed lever toward feed position, a valve for controlling the flow of fluid to said cylinder, means associated with said hand feed lever for actuating said valve simultaneously with the engagement of said interlocking elements to cause said piston to move said hand feed lever through its feed range to stop position, and means to release said interlocking elements so that said hand feed lever may be moved to starting position, such movement releasing said valve actuating means to cause said piston rod to return to starting position.

2. The combination with a grinding machine having a hand feed lever, of a cylinder, a fluid actuated piston in said cylinder having a piston rod projecting into the path of movement of said lever, interlocking elements associated respectively with said piston rod and said lever engageable upon movement of said lever toward feed position, a valve for controlling the flow of fluid to and from said cylinder, a cam associated with said lever for actuating said valve simultaneously with the engagement of said interlocking elements to cause said piston to move said lever through its feed range, and means to release said interlocking elements at the limit of feed movement of said lever to permit said lever to be manually moved to starting position and disengage said

cam from said valve to cause said piston to return to starting position.

3. The combination with a grinding machine having a hand feed lever, of a cylinder, a fluid actuated piston in said cylinder having a piston rod projecting from said cylinder into the path of said hand feed lever, interlocking elements associated respectively with said piston rod and hand feed lever engageable upon movement of said hand feed lever toward feed position, a valve for controlling the flow of fluid to said cylinder, means associated with said hand feed lever for actuating said valve simultaneously with the engagement of said interlocking elements to cause said piston to move said hand feed lever at a uniform rate through its feed range, and means to automatically release said interlocking elements at the limit of feed movement of said hand feed lever.

4. In combination with the hand feed lever of a grinding machine having a source of hydraulic fluid under pressure, hydraulically actuated means connected to said source for moving the hand feed lever including a cylinder, a piston in said cylinder having a piston rod projecting into the path of movement of said lever, interlocking elements associated with said piston rod and said lever engageable upon movement of said lever toward feed position, said piston serving to move said lever at a uniform rate through its feed range, and means to release said elements at the limit of feed movement of said lever.

5. In combination with the in-feed mechanism of a grinding machine, a cylinder, a fluid actuated piston in said cylinder having a piston rod adapted to be releasably connected to said mechanism, a valve for controlling the flow of fluid to and from said cylinder, a cam for actuating said valve simultaneously with the connection of said piston rod to said mechanism to move the latter through its feed range, and means to release said piston from said in-feed mechanism at the limit of its feed movement and disengage said cam from said valve to cause said piston to return to starting position.

WILLIAM MIGNONA.
